CIRCUIT BREAKER

Ralph M. Smith, Detroit, Mich.

Application February 21, 1934, Serial No. 712,273

7 Claims. (Cl. 200—87)

This invention relates to circuit breakers, the object being to provide a circuit breaker that automatically makes or breaks the circuit through centrifugal force or through use of an electromagnet or similar instrumentality.

The structure is one in which an armature is carried by a spring contact member within a vacuum tube or receptacle preferably formed of a transparent material such as glass, and a feature of the invention resides in the use of an armature at or near the contact end of the spring member for engaging a similar non-resilient contact member and in which the armature is of a tubular form positioned approximately on the axis of the tube and with the contact either closed or broken and further one in which the armature member being of considerable weight may be utilized in conjunction with an electrically operated rotated member in which the speed of rotation is to be controlled.

These objects and the several novel features of the invention are hereinafter more fully described and claimed, and the preferred form of construction of a circuit breaker embodying my invention is shown in the accompanying drawing in which—

Fig. 1 is a longitudinal section of my improved circuit breaker on an enlarged scale.

Fig. 2 is a representation principally diagrammatic in form showing the use of my circuit breaker to control a motor having a special function hereinafter described.

Fig. 3 is a perspective view showing my improved circuit breaker operating through centrifugal force.

One form of my improved circuit breaker is illustrated in Fig. 1 in which 1 indicates one form of a vacuum tube to which the lead wires 2 and 3 of a circuit extend and the terminals or tongues of which are indicated at 4 and 5 having contact points 6 and 7 respectively at the unsupported ends. The tongue 4 is of spring material, that is, resilient and flexible while the tongue 5 is comparatively rigid and non-resilient. The member 4 preferably also is formed with one or more loops to secure flexibility and resiliency and also has a portion 8 thereof attached directly as by brazing or welding to an armature 9 here shown as a tube through the open ends 4 of which both the contact terminals or tongues 4 and 5 extend. This armature is mounted at a distance from the point of support of the tongue members in the inturned base portion 10 of the tube and by which they are rigidly supported at this point. The tubular form of the armature provides a

shield for the contact points in the form shown in Figs. 2 and 3 and in any of the forms, within the scope of the appended claims, limits the extent of movement of the resilient member by reason of contact thereof with the container wall and functions either in the making or the breaking of the contacts by the inherent spring action of the resilient member in the form of the structure shown in Figs. 1 and 2 or through centrifugal force in the form shown in Fig. 3.

This circuit breaker is for more or less delicate work and heretofore, with contacts made in the open air, the arcing incident to the making and breaking of the circuit tends to within a short time destroy the efficiency of the device, the contacts being covered with a scale and burning out. By mounting the same in a vacuum or in a tube filled with an inert gas, such difficulties are practically completely avoided and a circuit breaker of long life is secured.

In the form of the invention shown in Figs. 1 and 2 the parts are so assembled that the contacts are normally open.

In the form of the tube in Fig. 1, the two input lines 2 and 3 are at the same end of the tube but, as illustrated in Fig. 2, the corresponding lines 21 and 22 are at opposite ends of the tube. However, in either case, the function and operation of the device is identical.

One use of the device is illustrated in Fig. 2 in which there is an electric circuit to a motor 30 controlling the length of the arc in a carbon lamp in which the two electrodes 31 and 32 are moved toward or from each other by the threaded shaft 33 on which the holders 34 and 35 for the respective carbon elements are in threaded relation, the threads 36 for the arm 34 being for instance right hand while the threads 37 are left hand. Thus, by rotation of the shaft 33 in one direction the carbons are caused to approach each other as the gap tends to lengthen by the burning away of the two oppositely disposed ends of the carbon elements. This illustration is more or less diagrammatic but is well known and understood by those familiar with the art. The shaft 33 is connected directly to a motor shaft or extension thereof indicated at 38.

The carbons are connected to a current source which includes the generator G and the wires 40—41 and 42 and to establish the arc the hand screw 43 for instance may be turned to bring the carbons to point of contact and then separated to draw the arc.

A magnet coil 44 is provided adjacent to the tube 1a of Fig. 2 and the tubular armature 9a

- the armature limiting movement of the resilient tongue when unrestrained by the magnet.
3. A circuit interrupter comprising a tube, electrically insulating material, a movable tongue therein having a contact point, a fixed non-resilient tongue lying in parallel relation with the movable tongue and having a contact for engagement with the contact point of the movable tongue, an armature of tubular form carried by the movable tongue and limitedly movable in the tube and thereby limiting the extent of movement of the movable tongue, said armature being adjacent the free end of the tongue and the opposite ends of both tongues being supported by the tube and respectively connected with lead-in wires of a circuit, and an electro-magnet exteriorly of the tube and so positioned that upon energization the armature is moved to change the relative position of the contact points and thus make or break a circuit as the case may be.
4. A circuit interrupter comprising an exhausted tube, a non-resilient non-vibratable tongue therein having a contact, a resilient tongue therein having a companion contact, both said tongues being supported at one end by the tube, a tubular armature within the said tube and secured to the resilient tongue, the said tongues extending into the interior of the tubular armature and an electro-magnet positioned exteriorly of the tube and adapted upon energization to move the armature and thereby change the normal position of the contact member to make or to break a circuit as the case may be, the said spring member restoring the contacts to the normal position upon de-energization of the magnet, said tubular armature limiting the extent of movement of the resilient tongue when unrestrained by the magnet.
5. A circuit interrupter comprising a tube adapted to shield the contact points from atmosphere to prevent arcing and scaling of the contact points, a pair of tongues in the tube, each supported at one end by the tube and extending longitudinally thereinto and each having a contact at its opposite end, one of the tongues being resilient and normally tending to maintain the points in a predetermined relationship, said resilient tongue being formed with a loop to provide increased resiliency, and a metal member

supported by the said spring tongue near its end and beyond the said loop providing a means through which force may act to move the contact of the resilient tongue from normal position to make or break a circuit as the case may be, the spring tongue acting to restore the contact points to normal relationship upon cessation of action of the disturbing force.

6. A circuit interrupter comprising a container of insulating material of hollow form and cylindrical interior wall, a pair of lead-in wires, a tongue associated with each lead-in wire, one of said tongues being resilient a terminal on the said tongues through contact of which the circuit of the lead-in wires is closed, an armature of tubular form on the resilient tongue, the other terminal being fixed in character and extending into the armature out of contact therewith, the outer diameter of the armature being less than the inner diameter of the container thereby limiting the movement of the armature by the resilient tongue and maintaining the same out of contact with the fixed tongue, and an electromagnet exteriorly of the container through energization of which the armature is moved to close the terminals.

7. A circuit interrupter comprising a tubular member, a pair of tongues extending longitudinally thereof, each of the tongues being supported within the tube and respectively connected at one end with the lead-in wires of a circuit, the opposite ends of the tongues each having a contact point, one of the tongues being inherently resilient and vibratable and the other of the tongue being non-resilient whereby the contact point thereof is maintained substantially in fixed position for engagement with the contact point of the resilient tongue, the resilient tongue tending to maintain the contact points in a predetermined relationship and tending to return to normal position subsequent to forcible movement from the predetermined relationship, and a metal member secured to the resilient tongue near its contact point and at a distance from the point of support thereof to secure maximum movement of its contact point within the tube by a disturbing force.

RALPH M. SMITH.
